UNITED STATES PATENT OFFICE.

CHARLES F. LEFEVER, OF PLYMOUTH, MICHIGAN, ASSIGNOR TO DAISY MANUFACTURING COMPANY, OF PLYMOUTH, MICHIGAN, A CORPORATION OF MICHIGAN.

LIQUID GUN.

Application filed July 18, 1927. Serial No. 206,637.

The invention relates to liquid guns and has for one of its objects to so construct the gun that it may be cheaply manufactured and assembled. Another object is to construct the trigger so that it may be easily connected to the liquid barrel of the gun and also engaged with the power storing spring of the gun. A further object is to so construct the frame that it will form the false barrel and handle of the gun and provide for engaging the trigger with the handle in such a way that the trigger will be normally held from disengagement from the handle. With these as well as other objects in view, the invention resides in the novel features of construction and combinations and arrangements of parts as more fully hereinafter set forth.

In the drawings:—

Figure 1 is a perspective view of the gun embodying my invention;

Figure 2 is a longitudinal section therethrough;

Figure 3 is a perspective view of the frame of the gun;

Figure 4 is a perspective view of the assembly, including the liquid barrel, piston and trigger of the gun;

Figure 5 is a cross section on the line 5—5 of Figure 2.

The gun has the frame 1 which is formed of sheet metal folded to produce the false barrel 2 and the handle 3 with the fold at the top of the false barrel. The false barrel has an open front end and a closed hemispherical rear end, the latter being secured by forming gores in the sheet metal before folding and by then closing these gores at the time of folding. The portions of sheet metal on opposite sides of the fold line are alike, each having a flange 4 depending from the front end portion of the false barrel and spaced from the other flange and the transverse flanges 5, 6 and 7, respectively, at the front rear and bottom of the handle 3, the corresponding transverse flanges meeting at their edges. 8 are corresponding terminal flanges extending from the bottom transverse flanges and rigidly secured to each other as by spot welding. The front transverse flanges 5 have corresponding notches 9 in their edges forming an opening for receiving the trigger of the gun. The frame being formed in this manner may be economically manufactured.

10 is the reciprocable liquid barrel telescopically engaging within the false barrel and having an open rear end and a closed front end formed with the restricted aperture 11. 12 is the trigger which is formed of wire bent to shape. This trigger has at its front end the hook 13 which extends through the wall of the liquid barrel for connecting the liquid barrel to the trigger and the downwardly offset guide portions 14 and 15 which extend substantially parallel to the false barrel, the former being located between the flanges 4 and the latter passing through the notches 9 in the front transverse flanges 5. The lowermost 70 guide portion 15 has the shoulder 16, which is preferably formed integral therewith as by a swaging operation and is forced between the front transverse flanges to occupy a position in rear thereof. By reason of 75 the front transverse flanges having their edges held in contact by the resilience of the metal, these flanges may be spread sufficiently far apart to provide for the insertion of the shouldered portion of the trigger, but will effectively hold the shouldered portion from accidental disengagement.

17 is the piston having the head 18 slideable within the liquid barrel 10 and the wire shank 19 which extends longitudinally 85 within the false barrel and has its rear end abutting the rear hemi-spherical end of the false barrel and centered thereby. 20 is a power storing coil spring encircling the shank 19 and having its front end portion 90 engaging under the hook 13 of the trigger and its rear end abutting the collar 21. This collar encircles the shank 19 and abuts the shoulder 22 formed upon the shank preferably by a swaging operation. 95

With this construction, the piston, the liquid barrel, the trigger, the power storing coil spring and the collar may be assembled as a unit and then placed in the frame to complete the gun. By having the coil 100 spring engaging the hook of the trigger assembly of the parts is facilitated and in the completed gun the liquid barrel and trigger will normally be held in their forward positions determined by the shoulder 16 of the trigger in contact with the front transverse flanges 5 of the handle. Furthermore, the strength of the coil spring and the normal position of the trigger and liquid barrel may be readily varied by swaging the 110

piston shank and the trigger to form the shoulders 22 and 16 at the desired points.

What I claim as my invention is:

1. In a gun, the combination of a frame, a reciprocable liquid barrel guided by said frame, a stationary piston cooperating with said barrel, a trigger connected to said barrel for moving the same in one direction, and a spring connected to said trigger adjacent to the point of connection of said trigger to said barrel for moving said barrel in the opposite direction.
2. In a gun, the combination of a frame, a reciprocable liquid barrel upon said frame, a stationary piston cooperating with said barrel, a trigger having a barrel connecting portion extending through a wall of said barrel, and a spring engaging said barrel connecting portion of the trigger for moving said barrel in one direction.
3. In a gun, the combination of a frame, a reciprocable barrel upon said frame, a stationary piston cooperating with said barrel, and a trigger for moving said barrel in one direction, said trigger having a hook extending through a wall of said barrel and a spring engaging said hook and connected to said piston for moving said barrel in the opposite direction and holding said piston stationary relative to said frame.
4. In a gun, the combination of a frame, a reciprocable barrel upon said frame, a stationary piston cooperating with said barrel and having a shank abutting said frame, a collar upon said shank, a trigger having a hook extending through a wall of said barrel for moving said barrel in one direction and a coil spring encircling said trigger shank and having portions engaging said hook and collar to move said barrel in the opposite direction and hold said piston stationary relative to said frame.
5. In a gun, the combination of a frame having a false barrel, a reciprocable barrel slidably engaging said false barrel, a stationary piston cooperating with said recipro-

cable barrel and provided with a shank abutting the end of said false barrel, said shank being formed with a shoulder intermediate its ends, a collar encircling said shank and abutting said shoulder, a trigger having a hook extending through a wall of said reciprocable barrel for moving the same in one direction, and a coil spring encircling said shank and engaging said hook and collar to move said reciprocable barrel in the opposite direction and hold said piston stationary relative to said false barrel.

6. In a gun, the combination of a sheet metal frame forming a false barrel with a closed hemi-spherical rear end, a reciprocable liquid barrel slidably engaging said false barrel, a piston having a head within said liquid barrel, and a shank engaging the hemi-spherical rear end of said false barrel, said shank being provided with a shoulder intermediate its ends, a collar encircling said shank and abutting said shoulder, a trigger having a barrel securing portion extending through a wall of said liquid barrel, and a coil spring encircling said shank and engaging said barrel securing portion of the trigger and said collar.

7. In a gun, the combination of a folded sheet metal frame forming a false barrel and handle, said handle having front transverse flanges meeting at their edges, a reciprocable liquid barrel slidably engaging said false barrel, a stationary piston cooperating with said liquid barrel, a wire trigger having a hook extending through a wall of said liquid barrel for connecting said liquid barrel to said trigger, and a shouldered portion insertable between said front flanges of said handle whereby the shoulder normally holds said trigger from disengagement from said handle, and a spring for yieldably holding said trigger in a position determined by the shoulder contacting with said front flanges. In testimony whereof I affix my signature.

CHARLES F. LEFEVER.
